UNITED STATES PATENT OFFICE.

RAYMOND C. MITCHELL, OF SPRINGFIELD, OHIO, ASSIGNOR TO THE WEBSTER & PERKS TOOL COMPANY, OF SPRINGFIELD, OHIO, A CORPORATION OF OHIO.

SHAFT-COOLING MEANS FOR GRINDING-MACHINES AND THE LIKE.

1,352,303.

Specification of Letters Patent.

Patented Sept. 7, 1920.

Application filed June 15, 1918. Serial No. 240,186.

To all whom it may concern:

Be it known that I, RAYMOND C. MITCHELL, a citizen of the United States, residing at Springfield, in the county of Clark 5 and State of Ohio, have invented certain new and useful Improvements in Shaft-Cooling Means for Grinding-Machines and the like, of which the following is a specification.

10 My invention relates to improvements in grinding machines, and provides a shaft mounting and shaft cooling construction that may be desirably employed in plain cylindrical grinders, and kindred mechanism for increasing the efficiency, accuracy and longevity of the machine by eliminating many troubles due to heating of the grinding wheel spindle.

Plain cylindrical grinders are commonly 20 subject to hard usage in that they are operated at high speed, and are apt to be called on for continuous service and deep-cutting action, and so it is usual practice to give the grinding wheel spindle a long bearing in 25 which the spindle must fit very snugly to attain the necessary accuracy in centering of the grinding wheel. Spindles, so mounted, however, are subject to deterioration by barking, scaling and rapid wear, 30 and this is due in large measure to the heat engendered in the shaft and bearings, which causes expansion that tightens the bearing and so enhances the initial heating and wearing action. Of course the ultimate results are inaccuracy in the work, or the alternative of frequent and extensive repairs.

To overcome these difficulties I propose to cool the grinding wheel spindle internally by the positive circulation therethrough of 40 a cooling liquid, or coolant, preferably the liquid (such as soap and water) that is commonly employed to cool the contacting surfaces of the work and wheel; and in the drawings I have illustrated an embodiment 45 of my invention in a form particularly available for a plain cylindrical grinder, the single view illustrating fragments of grinder mechanism and showing the wheel and its mounting in longitudinal section.

50 On the bed 10, in suitable relation to the head and tail stocks 11 and 12, by which the work is supported and rotated, the wheel stand 13 is mounted, such stand affording separated bearing brackets 15 and 16, through which the spindle or shaft 17

extends and between which the spindle-driving pulley 18 is mounted. Each of these bearing brackets is suitably equipped with bushings or brasses, and lubricating means to afford a close, well-lubricated 60 bearing for the spindle 17. The details of such equipment may be varied without departure from the spirit of my invention, the specific construction shown providing in connection with each bearing separated 65 bushing brasses 19 separated to admit the intermediate waste or other packing 20 to which the oil cup 21 delivers the lubricant, end caps 22 suitably packed as at 23 engaging threaded ends of the brasses to lock 70 them in suitably adjusted position. At the outward end of bearing 15 the cap 22' is preferably provided with a shoulder 25 and a threaded collar 26, receiving between them the races of a thrust ball bearing 27, 75 these races also engaging a shoulder 28 and threaded collar 29 near the extremity of the spindle 17.

The spindle 17 is hollow or provided with a central cooling passage 30 from a point 80 near its head end to its opposite end where it opens as at 31 for liquid delivery, and is preferably provided with a drip bead 32, its open end extending beyond the adjacent bearing and being within the open mouth 85 of a circular receiving chamber 33, which connects directly with an outward extending return pipe 34. The cooling liquid is supplied to the wheel-bearing end of the shaft, preferably within the end portion 90 overlain by the wheel, the shaft having an end wall 35 with an orifice 36, through which enters a stationary supply pipe 37 that is suitably connected to the supply main 38, leading from the pump 39, to the eye of 95 which pump the return pipe 34 aforesaid is led. Thus the cooling liquid circulated by the pump finds passage through the hollow shaft.

To make the circulation most effective I 100 provide within the shaft means for setting the liquid in whirl in its passage through the shaft, preferably in the same direction as the intended direction of rotation of the shaft so that by centrifugal action the cooling liquid is thrown against the shaft wall, but, since the cooling body is whirled in the same direction as the shaft, with minimum engendering of heat due to contact of the liquid with the shaft. In the particular con- 105 110

struction the end of pipe 37 is provided with a tapered spider 38' from the center of which projects a stem 39' carrying a spiral 40, which preferably makes several complete turns around the stem and extends close to, though not in contact with, the wall of the shaft. In practice the screw thus provided need extend only a minor portion of the length of the spindle as shown, for 10 the tendency of the shaft-rotation is to maintain the whirl when once started.

The wheel 42 is mounted on the tapered end of the shaft in ordinary fashion and the customary wheel guard 43 surrounding the 15 non-working peripheral portion of the wheel rigidly mounted on the frame, affords suitable anchorage for brackets 44 and 45 to support portions of the piping system.

20 In operation it will be apparent that the positively impelled liquid will flow through the shaft in whirl, keeping it cool and thus eliminating those disadvantages that arise from heating of the shaft and consequent 25 swelling thereof and resultant tightening of the fit between the shaft and its bearings,—effects that cumulatively tend toward undue and irregular wearing of the shaft and its bearings. The liquid flowing out of the remote end of the shaft is caught by the in- 30 closing casing, in whatever direction it may be thrown centrifugally, and is led back to the pump for further circulation.

While I have herein described in detail a 35 particular embodiment of my invention it will be apparent to those skilled in the art that change may be made in detail to adapt the construction to different specific machines, and otherwise to vary the specific 40 form of formal embodiment without departure from the spirit of my invention and within the scope of the appended claims.

What I claim is:

1. A combination of close fitting shaft 45 bearing and a shaft therein having a hollow center open at one end, liquid supply means leading into the opposite end of the shaft, liquid receptive means associated with the open end of the shaft, liquid impelling means 50 connected with the supply and receptive

means, and means for causing the fluid introduced into the shaft to whirl therein.

2. Cooling means for high speed spindles, of grinding-machine-wheels and the like, comprising, in combination, the spindle, a 55 long, snug bearing therefor, said spindle having a central bore from its load-carrying end and open at its remote end, a liquid circulating pump, piping for conducting liquid from said pump to the load carrying end of 60 the spindle and back to the pump from the opposite end, and a stationary screw member located within the bore close to the liquid receptive end thereof, to set the liquid passing through the shaft in whirl. 65

3. Cooling means for high speed spindles, of grinding-machine-wheels and the like, comprising, in combination, the spindle, long, snug bearings for said spindle, said spindle having a central bore extending 70 from its load carrying end and open at its remote end, a liquid circulating pump having delivery connection to a pipe entering the load carrying end of the spindle, said pipe supporting a screw member, free from 75 the spindle for whirling the liquid within the spindle, and a receptive casing encircling the remote, open end of the spindle and having return connection to the pump.

4. Cooling means for high speed spindles, 80 of grinding-machine-wheels and the like, comprising, in combination, the spindle, long, snug bearings for the said spindle, said spindle having a central bore extending from the load bearing end and open at the 85 remote end, said remote end of the spindle projecting beyond its bearing, a receptive casing enveloping the projecting end of the spindle, a liquid circulating pump with which said casing has connection, delivery 90 connections from said pump, including a pipe extending axially into the spindle bore, said pipe bearing a screw projecting axially of the spindle and having its lead in the direction of rotation of the spindle, whereby said 95 screw may set in whirl the liquid within the spindle in the same direction as that of the spindle rotation.

RAYMOND C. MITCHELL.
